HIGH PRESSURE SIGHT FEED

Walter H. Kniskern, Prince George County, Va.,
assignor to Atmospheric Nitrogen Corporation,
New York, N. Y., a corporation of New York

Application October 10, 1930. Serial No. 487,888

17 Claims. (Cl. 184—96)

This invention relates to sight feeds, and more particularly to sight feeds of the "bull's eye" type, in which a thick glass disk is employed to permit observation of the flow of drops of oil through a body of heavy, colorless liquid maintained in a sight feed chamber.

Numerous devices of this general class contemplated by the present invention have heretofore been proposed, and in many instances have been designed to meet different conditions arising in practice. While the broad ideas involved in the construction of such sight feeds are more or less parallel, it often occurs that known devices obtainable on the market are not adaptable 15 to adequately serve some operations. It has been found that such is the situation where it is necessary to periodically supply regulated quantities of lubricant to parts of machines, for example heavy duty compressors, where comparatively 20 high pressures exist at the point or points of delivery of the oil.

The present invention is directed to the construction of a sight feed particularly adaptable for service where it is required to deliver a lubricant against high pressures, say upwards of 1500 pounds per square inch. For operation under these conditions, the sight feed chamber and associated parts should desirably be of special construction to overcome the greatly increased tendency toward leakage, and to avoid frequent shutdowns for replacements and repairs. Accordingly, in one phase, the invention includes the provision of a block or casing forming a sight feed chamber having an opening adapted to receive a heavy sight glass, together with an assemblage of parts including principally a follower adapted to receive the thrust arising from the fluid pressure upon glass, a gasket interposed between the glass and the casing, and a spreader and spring reflector adapted to initially effect a tight joint between the glass and the casing. After the initial establishment of a tight joint at low pressures, the sealing is further effected during operation at high pressures by the action of the fluid pressure upon the rubber gasket, which is designed to yield under pressure in a manner which seals the joint more tightly.

The invention further comprises a particular design of sight feed chamber by reason of which substantial quantities of the colorless liquid in the chamber may become exhausted without permitting contact between the oil collecting in the top of the chamber and parts of the sight feed, specifically the gaskets, which are likely to become deteriorated by the action of the oil.

In another aspect, the invention is directed to a sight feed construction having associated therewith valve controlled ducts or conduits functioning in conjunction with a pump and a liquid reservoir to provide an arrangement for replenishing the supply of liquid in the sight feed chamber without disconnecting the sight feed from the associated oil pump, and while permitting the maintenance of an uninterrupted flow of oil through the sight feed chamber during the operation of replenishing the liquid supply in the sight feed chamber.

For a fuller understanding of the nature and objects of the invention, reference may be had to the following detailed description taken in connection with the accompanying drawing in which:

Figure 1 is an elevation of one embodiment of the present invention. Portions of Fig. 1 shown in section represent a vertical longitudinal section taken approximately on the line 1—1 of Fig. 3;

Fig. 2 is a vertical section on the line 2—2 of Fig. 1;

Fig. 3 is essentially a plan view, that portion shown in section being a horizontal section taken approximately on the line 3—3 of Fig. 2;

Fig. 4 is a vertical section through the pumping unit taken approximately on the lines 4—4 in Figs. 1 and 3;

Fig. 5 is a longitudinal vertical section of a cylindrical gasket spreader;

Fig. 6 is an elevation of the spreader looking from the right in Fig. 5, and

Fig. 7 is a vertical section of a resilient reflector.

Referring to the drawing, the reference numeral 10 indicates a block or casing including, for example, four individual sight feeds. As shown in Fig. 2 and in the sectional portion at the right end of Fig. 1, the block or casing 10 is cut out to form a series of sight feed chambers 11 and the associated upper auxiliary chambers 12, the purpose of which will hereinafter appear. Each sight feed chamber 11 has a cylindrical sight glass opening indicated generally at 13, Fig. 2, which terminates outwardly in an annular shoulder 14, and an enlarged internally threaded portion adapted to receive an externally threaded ring or follower 15. The inner end of the follower 15, beyond the threaded section, is of reduced cross-section, but is of such diameter as to effect the seating of the inner vertical surface of the ring 15 against the annular shoulder 14 in the block 10. Diametrically opposite

notches 18 are cut into the circumference of the follower 15 to permit the latter to be screwed into and out of the casing by the use of a suitable tool.

5 In Fig. 2, the several parts which together hold the sight feed glass 20 in place, and effect a fluid-tight joint between the casing and the glass are shown in such position as these parts occupy when the device is assembled and in use. When 10 the follower 15 is screwed down tight, the edge of the inner vertical surface thereof bears against the shoulder 14 and a thin annular gasket 21, of suitable material, interposed between the ring 15 and the shoulder 14 and the sight glass 20. The 15 thin gasket 21 bears no part in sealing the joint between sight glass 20 and cylindrical sight glass opening 13, but it is used to compensate for the minute irregularities on the surface of glass 20 and follower 15, and to so provide a more uniform 20 distribution of load between these contact surfaces. The follower 15 receives the thrust arising from the fluid pressure upon glass 20 and gasket 22. A tight joint between the sight glass and the casing 10 is effected by an annular, preferably rubber gasket 22 of U-shaped cross-section 25 surrounding the sight glass at the left end thereof, engaging the smooth portion in the sight glass opening 13 and the thin gasket 21 held against the inner face of the follower 15.

30 The initial establishment of a tight joint at low pressures, is effected by a cylindrical spreader, indicated generally by the reference numeral 24, and shown in section and in elevation in Figs. 5 and 6, respectively. The spreader 24 comprises 35 a ring-like body portion 25 having an annular extension 26 surrounding the sight glass and terminating in a bluntly-edged ring 27, the outer diameter of which is materially less than that of the extension 26. The body 25 of the spreader is slotted at 29 to facilitate the placing of the spreader in the sight feed chamber without interference with the oil feed nozzle hereinafter referred to. Diametrically opposite the slot 29 in the body of the spreader is an aperture 30 which permits the passage of liquid therethrough from the main chamber 11 into the upper chamber 12. The cylindrical spreader is longitudinally of such length that when the parts are in position as shown in Fig. 2, the blunt edge of the ring 27 projects some distance into the opening between the ends of the U-shaped gasket 22.

40 Interposed between the body of the spreader and the wall of the sight feed chamber 14 most remote from the sight glass is a resilient reflector disk 32. When the several parts are in place and the sight feed is ready for use, the disk 32 lies in a vertical plane against the wall of the chamber 11 as shown in Fig. 2. As will be seen, however, by reference to Fig. 7, the disk 32 itself is 45 dished or concaved sufficiently so as to exert a spring-like action on the spreader during and after assembly of the parts. The object of concaving the disk so that it may act as a spring is to insure a constant thrust upon spreader 24, causing it to enter the opening between the lips of gasket 22, thereby expanding it and effecting the initial sealing. By the provision of the spring effect in the disk 32 deviations from normal size of gasket, glass and spreader are also compensated for. During normal operation, i. e., operation at high pressures, the sealing is effected by the fluid pressure coming between the lips of gasket 22, forcing one side of the gasket against casing 10 and the other side against glass 20.

50 The concave face of the disk is polished so as

to provide a reflecting surface in the back of the chamber 11 thus facilitating ready observation through the glass of the passage of oil drops upwardly through the chamber 11.

55 Each of the four sight feeds in the casing 10 is provided at the bottom with an oil inlet 35, and at the top of the auxiliary chamber 12 with an oil outlet 36. A nozzle 37 is set into the upper end of the oil inlet 35 and projects vertically upward some distance into the interior of the sight feed chamber 11. The inlet oil passage 38 and the oil outlet 36 are internally threaded to receive the pipe connections 39 and 40. The conduit 39 is connected to the discharge side of any suitable force feed oil pump. As will be understood, the outlet connection 40 conducts the oil from the sight feed chamber to lubricate some part of the machine with which the sight feed is associated.

60 Referring now to the auxiliary chamber 12, it will be noted, by reference to Figs. 1 and 2, that this chamber is positioned directly above the sight feed chamber 11, and that the recess forming the chamber 12 is of substantial size. As is known in the art, the sight feed chamber 11 is adapted to contain some suitable comparatively heavy, colorless liquid through which the successive oil drops rise from the nozzle 37 to the chamber outlet. This liquid is usually a mixture of glycerine and water. Such mixture has practically no deteriorating effect upon the material 65 constituting the resilient gaskets which are used in devices of the type with which this invention is concerned. However, over a period of time, these gaskets are affected to such an extent as to give rise to leaks if permitted to come in contact with the oil continuously passing through the sight feed chamber. The principal purpose of the chamber 12 is to provide a means for readily avoiding any contact between the oil and the gasket 22. The chamber 12 is of substantial dimensions, and is adapted to hold a considerable portion of the body of glycerine-water mixture which is contained in the sight feed as a whole. The chamber 12 permits the ready maintenance of the level of the glycerine-water mixture substantially above the gasket 22 in spite of rather wide fluctuations in the total quantity of glycerine-water mixture in the sight feed, and thus avoids any possibility of contact between the gasket and the small amount of oil which is always present in the top of the sight feed chamber. For example, the level of the glycerine-water mixture in the chamber 12 may fall to or even below the dotted line 42 without permitting any contact between the oil and the gasket 22.

65 To place the device as thus far described in condition for operation, the disk 32 is placed against the rear wall of the chamber 11 with the concave polished surface facing outwardly. The spreader 24 is next inserted in the chamber 11 so that the slot 29 straddles the nozzle 37 and the aperture 30 in the body portion 25 is directly above the end of the nozzle 37. The plane surface of the ring 25 of the spreader will then contact the periphery of the disk 32. The glass 20 and the gasket 22 are then set in place, and the follower 15 screwed down until the periphery of the inner vertical surface thereof wedges the gasket 21 tight against the shoulder 14 on the casing. It will be noted that the follower 15 then bears directly against the annular shoulder 14, exerts no pressure directly against the glass 20, and is in a position which may be described as axially fixed. There is therefore no tendency to break the sight glass because of pressure applied di-

rectly on the glass to hold the latter in place. During the tightening of the follower 15, the blunt ring 27 on the spreader gradually becomes embedded between the lips of the gasket 22, and 5 when the follower 15 is seated against the shoulder 14, the disk 32 becomes substantially flattened. The combined action of the spreader 24, the follower 15, and of the spring-like effect of the disk 32 exerts pressure on the gasket 32 and 10 thus serves to spread the same in a direction radially of the glass and effects the initial sealing between the glass and the body of the casing 10.

When the chambers 11 and 12 are filled with a suitable colorless liquid heavier than the oil to 15 be employed for lubricating purposes, and the conduits 39 and 40 are connected respectively, to the pump and the machine to be oiled, drops of oil, in quantities regulated by the output of the force feed oil pump, pass upwardly from the end 20 of the nozzle 37 through the liquid in the chamber 11, through the aperture 30 in the spreader 24, into the auxiliary chamber 12 and out through the connection 40 to the point of use.

During the operation of sight feeds of the type 25 contemplated in the present invention, small quantities of the glycerine-water mixture in the sight feed chamber are from time to time carried out of the chamber along with the oil leaving through the outlet. Thus, over a more or less 30 extended period, the supply of glycerine-water mixture in the sight feed chamber becomes gradually diminished, and, ultimately, it becomes necessary to stop the force feed pump and disconnect the sight feed therefrom, in order to 35 replenish the supply of heavy liquid in the sight feed chamber. Such a shut-down is highly undesirable, particularly where the sight feed is being used in connection with a continuously operating engine or machine. The present invention 40 contemplates a mode of replenishing the supply of glycerine-water mixture in the sight feed chamber without shutting down the force feed pump, and while permitting the continuous passage of oil through the sight feed chamber 45 as usually required by the machine being oiled.

Beneath the sight feed chambers, the block 10 is provided with a longitudinal duct 45 of 50 diameter sufficient to hold and facilitate the passage therethrough of a substantial quantity 55 of glycerine-water mixture. The longitudinal duct is closed at one end by a plug 46, and communicates at its opposite end with the discharge side of a force pump, indicated generally by the reference numeral 47, shown in section in Fig. 4. The conduit 45 communicates with the inlet 35 and the oil passage 38 of each sight feed chamber by means of transverse ducts 48, Figs. 2 and 60 3. The passage of liquid through a channel 48 is controlled by a needle valve 49 adapted to 65 seat in the forward end of a passage 48. The valve needle is formed integrally with the spindle 50 threaded into an opening in the block 10 as indicated at 51 in Fig. 3. Leakage of glycerine-water mixture from the conduit 45 around 70 spindle 50 to the outside of the block is prevented by packing 53 held in place by the gland 54 and bolts 55 threaded into the block. From a consideration of Figs. 1 and 3, it will be apparent that the admission of the glycerine-water 75 mixture from the duct 45 to any sight feed chamber is selectively controlled by the manual operation of the associated valve needle 49.

The pump unit 47, for forcing the glycerine-water mixture into the conduit 45 and thence into any one of the sight feed chambers as re-

quired, is shown in Figs. 1 and 3, and in section in Fig. 4. The base 60 of the pump is cut out to provide a suitable chamber for the valve cage 61 which is rigidly held in the position shown in Fig. 4 by engagement with the lower end of the pump cylinder 62 threaded into the base 60. The discharge side of the pump unit, controlled by the discharge valve 64, communicates with a transverse passage 65 passing through a cylindrical extension 66 which is adapted to be set into a recess formed in the end of the block 10 at the open end of the duct 45. A liquid-tight connection is maintained between the extension 66 and the block 10 by a gasket 67. The pump unit as a whole is attached to the block 10 by bolts 68 passing through the base 60 and threaded at their inner ends into the block 10 as indicated at 69 in Fig. 3.

Reference numeral 70 indicates a liquid reservoir mounted on the base 60, and communicating with the inlet side of the cylinder through the passage 71 controlled by the inlet valve 72. A piston 74, having on its lower end a suitable packing ring 75, is reciprocated in the cylinder 62 in the present construction of the pump unit 100 by the manually operated handle 76. The link 78 is pivotally connected at 79 to the base 60, and at its opposite end, as at 80, to the end of the lever 76. The manipulation of the piston 76 will be apparent from a consideration of Fig. 4. 105

During the normal operation of each of the sight feeds, all the valves 49 are closed, and the conduit 45 is maintained full of liquid. If it becomes necessary to replenish the supply of glycerine-water mixture in any of the chambers, 110 valve 49 is first opened, and the pump is manipulated to force the necessary quantity of glycerine-water mixture, drawn from the reservoir 70, through the duct 45, passage 48, inlet 35, through the nozzle 37 and into the chambers 11 and 12. 115 When a sufficient amount of glycerine-water mixture has been injected into the sight feed chamber, the associated valve 49 is then closed, and operation of the pump 47 discontinued. It will be observed that this construction permits 120 replenishing of the liquid supply in the chambers 11 and 12 without in any way interfering with the steady flow of oil entering the sight feed through the conduit 39 and leaving through the outlet 40.

Since certain changes may be made in the 125 above construction, and different embodiments of the invention may be made without departing from the scope thereof, it is intended that all matter contained in the above description or shown in the accompanying drawing shall be 130 considered as illustrative and not by way of limitation.

I claim:

1. In a sight feed, the combination with a casing having a sight feed chamber of an axially fixed follower engaging the casing, a sight glass seated against the follower, a gasket engaging the casing and the sight glass, and means for spreading the gasket to form a tight joint between the casing and the glass. 135

2. In a sight feed, the combination with a casing having a sight feed chamber of a follower engaging the casing, a sight glass seated against the follower, a gasket engaging the casing and the sight glass, and a member supported by a 140 wall of the sight feed chamber for spreading the gasket to form a tight joint between the casing and the glass.

3. In a sight feed, the combination with a casing having a sight feed chamber of a follower 145

- engaging the casing, a sight glass seated against the follower, a gasket engaging the casing, the follower and the sight glass, and a member supported by a wall of the sight feed chamber for spreading the gasket to form a tight joint between the casing and the glass.
4. In a sight feed, the combination with a casing having a sight feed chamber of a follower engaging the casing, a sight glass in the casing, a gasket interposed between the glass and the casing, and a member supported by a remote wall of the sight feed chamber and cooperating with the follower for spreading the gasket to form a tight joint between the casing and the glass.
5. In a sight feed the combination with a casing having a sight feed chamber of a follower engaging the casing, a sight glass in the casing, a gasket engaging the casing, the follower and the sight glass, and means interposed between the gasket and a remote wall of the sight feed chamber and cooperating with the follower for spreading the gasket to form a tight joint between the casing and the glass.
6. In a sight feed, the combination with a casing having a sight feed chamber of a follower threaded into the casing, a sight glass in the casing, a gasket interposed between the glass and the casing, a spreader supported by a remote wall of the sight feed chamber and having an extension engaging the gasket and coacting with the follower to spread the gasket to form a tight joint between the casing and the glass.
7. In a sight feed, the combination with a casing having a sight feed chamber of a follower threaded into the casing, a sight glass seated against the follower, a gasket interposed between the glass and the casing, a spreader supported by a wall of the sight feed chamber and having an annular extension surrounding the glass, the said extension engaging the gasket and coacting with the follower to spread the gasket to form a tight joint between the casing and the glass.
8. In a sight feed, the combination with a casing having a sight feed chamber of a follower threaded into the casing and abutting an annular shoulder thereon, a cylindrical sight glass in the casing, an annular gasket interposed between the glass and the casing, a spreader supported by a wall of the sight feed chamber and having an annular extension surrounding the glass, the said extension engaging the gasket and coacting with the follower to spread the gasket to form a tight joint between the casing and the glass.
9. In a sight feed, the combination with a casing having a sight feed chamber of a follower engaging the casing, a sight glass seated against the follower, a gasket engaging the casing, and the sight glass, and means including a resilient member interposed between the gasket and the casing for forming a tight joint between the casing and the glass.
10. In a sight feed, the combination with a casing having a sight feed chamber of a follower engaging the casing, a sight glass seated against the follower, a gasket engaging the casing and the sight glass, a spreader abutting the gasket and a resilient member interposed between the spreader and the casing.
11. In a sight feed, the combination with a casing having a sight feed chamber of a follower engaging the casing, a sight glass seated against the follower, a gasket engaging the casing and the sight glass, a spreader abutting the gasket and a reflector interposed between the spreader and the casing.
12. In a sight feed, the combination with a casing having a sight feed chamber of a follower engaging the casing, a sight glass seated against the follower, a gasket engaging the casing and the sight glass, a spreader abutting the gasket and a resilient reflector interposed between the spreader and the casing.
13. In a sight feed, the combination with a casing having a sight feed chamber of a follower engaging the casing, a sight glass in the casing, a gasket interposed between the glass and the casing, a spreader bearing at one end against the gasket and at the other against a resilient reflector resting against a wall of the sight feed chamber, the spreader coacting with the follower to expand the gasket to form a tight joint between the casing and the glass.
14. In a sight feed, the combination with a casing having a sight feed chamber of a follower threaded into the casing and abutting an annular shoulder thereon, a cylindrical sight glass seated against the follower, an annular gasket interposed between the glass and the casing, a spreader having an annular extension surrounding the glass and engaging the gasket, a disk-like resilient reflector bearing against the wall of the sight feed chamber remote from the glass, said disk at its periphery contacting the spreader, the spreader coacting with the follower to expand the gasket to form a tight joint between the glass and the casing.
15. A sight feed comprising a casing forming a sight feed chamber having an oil inlet at the lower end and an oil outlet at the upper end and adapted to contain a heavy liquid, a sight glass opening in the chamber, means including a gasket for forming a tight joint between the sight glass and the casing, and an enlarged auxiliary chamber in the casing between the top of the sight glass opening and the oil outlet whereby the liquid level in the sight feed may be maintained above the sight glass opening to avoid deterioration of the gasket.
16. A sight feed comprising a casing forming a sight feed chamber therein adapted to contain a heavy liquid, an oil inlet and an oil outlet for the chamber, an oil passage connected to the inlet, a second passage connected to the oil inlet, and means for forcing heavy liquid through the second passage into the chamber while continuing the uninterrupted flow of oil from the oil passage through the sight feed chamber.
17. A multiple sight feed comprising a casing having a plurality of sight feed chambers therein, each chamber being adapted to contain a heavy liquid and having an oil inlet and an oil outlet, a heavy liquid conduit in the casing, connections between the conduit and the inlet of each sight feed chamber, and means including said conduit and connections for replenishing the heavy liquid supply in a sight feed chamber while maintaining the flow of oil through the said chamber.

WALTER H. KNISKERN.
